UNITED STATES PATENT OFFICE.

CHARLES DE YOOS, OF NEW YORK, N. Y.

DESIGN FOR A COMBINED STAND AND RACK.

44,236.

Specification for Design.

Patented June 24, 1913.

Application filed April 28, 1913. Serial No. 764,285. Term of patent 7 years.

To all whom it may concern:

Be it known that I, CHARLES DE YOOS, a citizen of the United States, residing at the city of New York, borough of Brooklyn, in the county of Kings and State of New York, have invented a new, original, and ornamental Design for a Combined Stand and Rack, of which the following is a specification, reference being had to the accompanying drawing, forming part thereof.

The figure is a perspective view of a combined stand and rack, showing my new design.

I claim:

The ornamental design for a combined stand and rack, as shown.

CHARLES DE YOOS.
